CLAIM

The ornamental design for a combined detachable tool backpack and base, as shown and described.

DESCRIPTION

FIG. 1 is a perspective view of a combined detachable tool backpack and base showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the base of the combined detachable tool backpack and base showing my new design;

FIG. 10 is a perspective view of FIG. 9 from another angle;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a top plan view of FIG. 9;

FIG. 16 is a bottom plan view of FIG. 9;

FIG. 17 is a perspective view of the combined detachable tool backpack and base, in a state of use; and,

FIG. 18 is an exploded perspective view of the combined detachable tool backpack and base.

The broken lines shown in the drawings represent portions of the combined detachable tool backpack and base that form no part of the claimed design.

1 Claim, 18 Drawing Sheets
